(57) **CLAIM**

The ornamental design for a patient positioning device, as shown and described.

DESCRIPTION

FIG. 1 is a front perspective view of the patient positioning device, showing the patient positioning device mounted onto a stand having a seat and foot pad.

FIG. 2 is a close up front perspective view of the patient positioning device.

FIG. 3 is a top plan view of the patient positioning device.

FIG. 4 is a bottom plan view of the patient positioning device.

FIG. 5 is a rear elevation view of the patient positioning device.

FIG. 6 is a front elevation view of the patient positioning device.

FIG. 7 is a left side elevation view of the patient positioning device; and,

FIG. 8 is a right side elevation view of the patient positioning device.

The broken line showing is for illustrative purposes and forms no part of the claimed design.
